UNITED STATES PATENT OFFICE.

HANS SCHONBOE, OF OMAHA, NEBRASKA.

LIFE-SAVING MATTRESS.

933,671.

Specification of Letters Patent. Patented Sept. 7, 1909.

Application filed March 12, 1909. Serial No. 482,955.

To all whom it may concern:

Be it known that I, HANS SCHONBOE, a citizen of the United States, residing at Omaha, in the county of Douglas and State 5 of Nebraska, have invented new and useful Improvements in Life-Saving Mattresses, of which the following is a specification.

This invention is an improved life saving mattress for use in saving persons who jump 10 from windows of houses which are on fire and the said invention consists in the construction, combination and arrangement of devices hereinafter described and claimed.

The object of this invention is to provide 15 an improved life saving mattress which is supported on springs and which yields when persons jump upon it so as to absorb the shock and prevent the person from being injured by the jump.

20 In the accompanying drawings:—Figure 1 is a side elevation of a life saving mattress constructed in accordance with this invention, a portion of one of the side aprons being removed. Fig. 2 is a plan view of the 25 same. Fig. 3 is an end elevation of the same. Fig. 4 is a detail vertical sectional view of a modified construction. Fig. 5 is a detail transverse sectional view of the same.

In accordance with my invention I pro- 30 vide a suitable frame or base 1 which may be mounted on the bed or running gear of a vehicle so that it may be readily disposed in the required position under the windows from which the persons are to jump from the 35 burning building. At the corners of the said frame are vertical standards or posts 2 which rise therefrom and are provided at their upper ends with knobs or caps 3.

A frame 4 which carries a mattress 5 is 40 vertically movable and is provided at its corners with irons 6 which form guiding eyes through which the standards or posts extend, the said guiding eyes serving to connect the corners of the mattress frame to the 45 standards or posts and to permit said mattress frame and said mattress to move vertically. Supporting springs 7, which are here shown as coil springs, are placed on the standards or posts below the guiding eyes 50 and bear on the frame 1, said springs serving to normally maintain the mattress and its frame in the initial elevated position, shown in Figs. 1 and 3, and to yield when a person jumps upon the mattress so as to 55 absorb the shock and prevent the person

from being injured. Check springs 8 which are similar in construction to the springs 7 are placed on the upper portions of the standards or posts 2 and bear between the 60 guiding eyes 6 and the knobs or caps 3, the 60 said springs serving to check the upward rebound of the mattress, as will be understood, said springs 7 and 8 co-acting to permit the mattress to describe vertical movements in reverse directions immediately after 65 a person has landed upon the mattress, so that the shock of the landing becomes entirely absorbed and the person is uninjured.

At the sides of the mattress are aprons 9 which in practice may be made of canvas 70 or of any other suitable fabric. The said aprons are stretched between the corner posts or standards, have their upper corners connected thereto as by means of straps 10 which are here shown as engaging buttons 75 11 on the knobs 3, and the lower edges of the aprons are attached to the sides of the mattress frame. The width of the apron is such that when the mattress and mattress frame are in their normal position midway 80 between the ends of the standards or posts, the lower portions of the aprons are doubled. As the mattress descends under a shock such as caused by a person landing 85 thereon, the said aprons become tightened 85 and the aprons prevent the person from falling from the mattress as will be understood.

In Figs. 4 and 5 of the drawings I show a modified construction in which the standards or posts 12 are tubular and provided 90 in their inner sides with vertical slots 13. The supporting springs 14 and check springs 15 are placed in the said standards or posts and the corner irons 16 of the mattress frame 17 are provided with heads 18 95 which operate in the said tubular standards or posts between the ends of the springs 14, 15 and have necks 19 which operate in the slots 13.

100 I claim:—

1. The herein described life saving device comprising a frame, guide posts on the frame, a vertically movable mattress connected to and guided by the guide posts, cushioning springs below and check springs 105 above the mattress, said springs being carried by the guide posts, and side aprons attached at their upper sides to the guide posts and at their lower sides to the sides of the mattress, said aprons being normally 110

slack when the mattress is in initial position and tightened by the movement of the mattress as the latter descends.

2. In a device of the class described, the combination of a mattress, means for mounting the same for vertical movement thereof, yieldable cushioning devices for the mattress, and aprons for the sides of the mattress normally slack when the mattress is in

initial position and tightened as the mat- 10 tress descends.

In testimony whereof I affix my signature in presence of two witnesses.

HANS SCHONBOE.
